JOHN T. MYERS, OF ST. ANDREWS, FLORIDA

DISTILLING PLANT

Application filed August 10, 1928. Serial No. 298,638.

- This invention has reference to an apparatus for extracting from pine wood the vapors emanating therefrom for producing turpentine and other products.
- 5 The invention relates particularly to the extracting of tar and turpentine from pine wood and its primary object is the provision of a method and means for this purpose that includes a retort in which the wood is piled and subjecting the entire interior of the retort to a continuous pressure of moistened heat to force the vapors out of the wood and to then force the vapors into a conduit laid along the side, bottom or top of the retort,
- 10 so that the vapors are held in the conduit to further heat and reduce the same, as well as to cause the conduit with the heated vapors therein to assist in reducing or cooking the wood and thereafter conducting such vapors
- 15 from the conduit through a valve controlled pipe into a condenser so that the wood will be distilled without producing tar and further wherein heavy distillations, such as tar will be directed out of the retort.
- 20 The invention will be fully and comprehensively understood from a consideration of the following detailed description when read in connection with the accompanying drawings which form part of the application, with
- 25 the understanding, however, that the improvement is capable of extended application and is not confined to the exact showing of the drawings nor to the precise construction described and, therefore, such changes and
- 30 modifications may be made therefrom as do not affect the spirit of the invention nor exceed the scope thereof as expressed in the appended claims.
- In the drawings:
- 40 Figure 1 is a top plan view of a wood distillery in accordance with this invention.
- Figure 2 is a sectional view approximately on the line 2—2 of Figure 3.
- 45 Figure 3 is a transverse sectional view on the line 3—3 of Figure 2.
- Figure 4 is a detail longitudinal sectional view through one of the steam or water conducting pipes.
- 50 Referring now to the drawings in detail, the numeral 1 designates the retort. The
- front, back and bottom walls of the retort are preferably constructed of concrete, the bottom wall gradually inclining from the front wall to the back wall. The front is provided with the usual opening that is closed by a metal door 2, and the open top of the retort has arranged transversely thereon angle or like irons 3, upon which rests and is secured the top plate 4. The top plate 4 is designed to be covered with sand. The sides of the retort are of metal and are indicated by the numerals 5. These sides are arranged at an inclination so that the retort is gradually widened from its bottom to its top. The metal plates 5 provide the inner faces of brick furnaces which are arranged the entire length of the retort and each of these furnaces at the rear of the retort is provided with a chimney stack 7.
- 55 Arranged longitudinally along the top and adjacent to the plates 5 there are steam conducting pipes 7. The longitudinal branches of these pipes are provided with spaced apertures 8 directed angularly toward the plates 5 and the connecting element or pipe 9 for the longitudinal branches comprises sections which are centrally coupled for the reception of a pipe 10 that leads to the top of the retort and which is connected with a suitable source
- 60 of steam or water supply.
- 65 The doors for the furnaces 6 are arranged at the front of the device and are indicated by the numerals 11, respectively.
- 70 Buried at the rear of the retort slightly below the lower wall or inclined floor 13 thereof there is a concrete tank 14. This tank is designed to be partly filled with a fluid, sufficient to immerse the open face of a substantially rectangular trap 15 therein, the said trap 15 being piped, as at 16, through the rear wall of the retort in a line with the floor
- 75 13 thereof.
- 80 In the showing of the drawings I have illustrated resting upon the floor 13 of the retort a pipe with a comparatively large bore and which pipe is in the nature of a vapor conduit. This pipe is indicated by the numeral 17 and has at its forward end an upwardly directed U-coupling 18. The conduit 17, at its rear end, which is arranged in close prox-

inity to the rear wall of the retort has coupled thereto a vertically directed pipe 19 and this pipe has its upper end, which terminates only a slight distance from the top of the retort coupled to a pipe 20 which leads through the rear wall of the retort and which is connected to a vapor condenser 21. The pipe 20 has its passage controlled by a hand operated valve 22.

The wood is piled in the retort in the usual manner and the fire is started in the furnaces 6. The top of the retort and the side plates 5 are of steel. Initially the valve 22 is turned off, and as the wood is heated, the retort is filled with hot steam from the pipes 7. This vapor is directed against the steel plates 5. As the wood is heated the retort is filled with hot vapor, which when driven out of the wood rises to the top of the retort until the said retort is full of hot vapor. From the accumulation of this hot vapor in the retort a pressure is developed. The vapor is then forced through the pipe 17, and when the valve 22 is opened, out and into the condenser 21. By the arrangement of the conduit for the vapor the retort is full of hot vapor all of the time which heats and reduces the wood to charcoal. By this arrangement the coldest vapors are taken from the retort, the hot vapors remaining in the retort for heating purposes. This makes it possible to heat the wood uniformly throughout and as the heat increases there is finally a retort full of hot vapors from top to bottom and these vapors reduce the wood to charcoal. Obviously the conduit or vapor pipe 17 could be elevated above and arranged adjacent either side of the retort instead of being positioned near the bottom of the retort should the same be found desirable. This is accomplished by swinging the conduit pipe 17 and its branch 19 on the latter's threaded connection with the outlet pipe 20, and also turning the U-coupling 18 to a vertical position. In this event the coupling 18 would extend a greater distance above the angle pipe 16 as the tar or heavy vapors find a passage through this passage 16 and enter the trap in the well 14. An object of the pipes 7, in addition to creating a moistened heat in the retort is to prevent the sides of the retort from becoming red hot when first heated and before the vapors are driven out of the wood as the said sides are sprayed from the steam or water from the pipes 7.

This steam also supplies the moisture that is necessary in the first operation of the distillation and also prevents explosion in the retort which might otherwise occur from wood naptha or other explosive gases.

With my device the coldest vapors are taken from the retort, the hot vapors remaining to reduce the wood, and pressure is obtained which makes the heat uniform throughout the retort. The hot vapors in the conduit materially assist in reducing the wood.

Having described the invention, I claim:

1. A distilling plant for wood comprising a retort, whose bottom is inclined from its front to its rear, said retort having a top made up of metal beams and a sand holding plate supported by and arranged over the beams, furnaces at the sides of the retort, the inner walls of the furnaces comprising steel plates, a tank at the rear and below the bottom of the retort, an angle pipe entering the rear at the bottom of the retort, a box-like trap on the angle pipe received in the tank, apertured steam supply pipes in and arranged along the top and sides of the retort for directing steam against the side plates of the retort, a conduit pipe normally lying on the top of the bottom of the retort, having a U-coupling at one end, and a vertical branch at its opposite end, which branch is disposed in close proximity to the rear wall of the retort, an outlet pipe connected to the branch and extending through the rear wall of the retort, said outlet pipe having its passage valve controlled, and a condenser to which the outlet pipe is connected.

2. An apparatus for distilling wood comprising a retort that includes a closed receptacle whose bottom is inclined from its front wall to its rear wall, furnaces at the sides of the retort and the division walls between the furnaces and the retort being of metal, a tank at the rear and below the bottom of the retort, a tar outlet pipe directed through the rear wall and arranged in a line with the bottom of the retort, and having an angle end disposed over the tank, a box-like trap on said end of the pipe received in the tank, a conduit pipe for light vapors arranged in the retort having one of its ends provided with a U-coupling and its second end provided with a vertical branch, an outlet pipe received through the rear wall of the retort and threadedly connected with the branch of the vapor conduit to permit of the said conduit being swung to various angles in the retort, a valve controlling the passage through the outlet pipe, a condenser to which the said pipe is connected, apertured steam supply pipes in and arranged along the top at the sides of the retort, for directing steam against the metal plates that provide the sides of the retort.

3. An apparatus for distilling wood comprising a retort that includes a closed receptacle whose bottom is inclined from its front wall to its rear wall, furnaces at the sides of the retort and the division walls between the furnaces and the retort being of metal, a tank at the rear and below the bottom of the retort, a tar outlet pipe directed through the rear wall and arranged in a line with the bottom of the retort, and having an angle end disposed over the tank, a box-like trap on said end of the pipe received in the tank, a conduit pipe for light vapors arranged in the retort, having one of its ends provided with a U-

coupling and its second end provided with a vertical branch, an outlet pipe received through the rear wall of the retort and threadedly connected with the branch of the vapor conduit to permit of the said conduit being swung to various angles in the retort, a valve controlling the passage through the outlet pipe, a condenser to which the said pipe is connected, apertured steam supply pipes in and arranged along the top at the sides of the retort, for directing steam against the metal plates that provide the sides of the retort, and the said metal sides of the retort being arranged at inward angles whereby to gradually increase the width of the furnaces from the bottom to the top portions thereof.

In testimony whereof I affix my signature.

JOHN T. MYERS.
